STAPLETON D. GOOCH, OF LAKE WALES, AND WILLIAM H. WAGGAMAN, OF LAKELAND,
FLORIDA, ASSIGNEES TO CORONET PHOSPHATE COMPANY, OF NEW YORK, N. Y., A
CORPORATION OF NEW YORK

METHOD OF OXIDIZING PHOSPHORUS

No Drawing.

Application filed April 15, 1930. Serial No. 444,606.

This invention relates to an improved method of treating phosphorus and more particularly to a method of oxidizing phosphorus and producing phosphoric acid.

5 The present method has been devised so as to provide a simple and economical process of procuring relatively pure phosphoric acid from relatively impure phosphorus, without, as has heretofore been the practice, 10 subjecting the impure phosphorus to a preliminary purification treatment.

The method described herein is therefore particularly applicable to the treatment of phosphorus containing dust or other solid 15 impurities and is especially efficacious in treating wet phosphorus.

A major object of the invention is to produce substantially pure, strong phosphoric acid from relatively impure phosphorus.

20 Another object is to treat wet phosphorus in a novel manner so as to simultaneously effect complete oxidation of the phosphorus and humidification.

A further object is to provide a novel 25 method of burning impure phosphorus.

With these and other important objects in view, the invention comprehends the direct and complete combustion of impure and/or wet phosphorus so as to form phosphorus 30 pentoxide substantially free from impurities and effectively utilize the heat of combustion of the phosphorus to generate water vapor which provides the absorbing medium for the phosphorus pentoxide to form concentrated phosphoric acid.

The present treatment is especially, although not exclusively, adapted for use with a phosphorus sludge prepared by decomposing a phosphatic charge in a blast furnace 40 and condensing and collecting the elemental phosphorus together with solid impurities.

The method comprises feeding such impure phosphorus by any suitable means such as by gravity, by a pump, by a drag or screw 45 conveyor into one end of a rotary burner. The burner may be of the type used in burning sulphur for the production of sulphur dioxide in the contact process for preparing sulphuric acid. The burner may, if desired, 50 be inclined toward the exit end to facilitate

longitudinal movement of material. This element is preferably lined with some acid-proof and refractory material and, if desired, may be provided with vanes, baffles or other surface increasing means.

55 The impure phosphorus or phosphorus sludge is fed in at one end and as the burner rotates it is distributed over the inner surface. During its passage through the burner the phosphorus is exposed to a draft of air preferably admitted at a point adjacent the feeding point of the phosphorus. The air may be admitted under reduced or forced draft and may be controlled to any desired degree as to temperature and volume so as to regulate the speed and extent of combustion. It will be observed that since the inner walls of the burner are composed of a refractory material heat loss is largely prevented and the full thermal value of the combustion is utilized. By reason of this the inner surfaces are maintained uniformly hot and hence condensation of vapors within the burner is prevented.

In these circumstances a portion of phosphorus is burned or oxidized directly while the heat generated vaporizes or sublimes a substantial quantity of the element. It will be observed, however, that by insuring a longer path of travel for the phosphorus and by controlling the temperature within the burner, the phosphorus may be substantially completely oxidized within the burner.

70 In the preferred modification, the products of combustion are led from the rotary burner to a separate combustion chamber where an additional quantity of air preheated to any desired degree is admitted. This treatment insures the combustion of any residual unoxidized phosphorus.

75 It will be observed that due to the thermal conditions of the operation, any water contained in the phosphorus charge is transformed into steam and this is available to humidify the phosphorus pentoxide either in the burner, combustion chamber or in the absorption system. In the case of a charge of phosphorus containing fifty per cent or more of moisture, this water is converted to steam and on reaching the absorbing tower or Cottrell precipitator for collecting the acid,

furnishes, at least, a portion of the water required to produce phosphoric acid of high concentration.

The absorbing system may comprise either 5 conventional absorbing towers or a Cottrell precipitator, or both in series, the structure and function of each of which is well known to those skilled in the art.

In some circumstances, as where the phosphorus is burned at a relatively rapid rate, it 10 is often necessary to cool the combustion gases before passing them to the absorbing units. This may readily be done by interposing a suitable cooling means between the combustion chamber and the absorbing units. As a 15 typical example of a means of achieving this reduction of temperature, a cooling tower may be provided. In this the gases may be introduced into the lower end and sprayed 20 with water, so as to reduce the temperature to such a degree as will permit of ready absorption or precipitation. Obviously, however, the gases may be cooled in any other manner as by indirect contact with a cooling 25 medium.

It will be observed that the process described herein provides a simple and effective 30 method of treating impure phosphorus to prepare phosphoric acid. Any solid impurities contained in the phosphorus are left behind as a residue in the burner or combustion chamber. The heat generated by the combustion of the phosphorus is utilized to vaporize the contained water and render it 35 available for humidification. The method, therefore, provides, so to speak, for a simultaneous oxidation and humidification of the phosphorus, which are secured by a single treatment of one material, that is the wet 40 phosphorus.

Therefore, while a preferred modification 45 of the invention has been described it is to be understood that this is given merely as a typical example of the manner in which the principles involved herein may be effectuated.

We claim:

1. A method of producing phosphoric acid 50 from an impure wet sludge containing elemental phosphorus comprising feeding the phosphorus sludge into one end of a rotary burner, causing combustion of the phosphorus, leading gases and vapors from the burner into an auxiliary combustion chamber and subsequently separating the phosphoric acid contained in the combustion 55 gases.

2. A method of producing phosphoric acid 60 from an impure wet sludge containing a mixture of yellow and red phosphorus, comprising feeding the phosphorus sludge into one end of a rotary burner, causing combustion of the phosphorus, leading gases and vapors into an auxiliary combustion chamber, and then subsequently separating the 65

phosphoric acid contained in the combustion gases.

3. A method of supplying water sufficient for the production of phosphoric acid from phosphorus pentoxide comprising burning impure wet phosphorus sludge in a rotary burner, admitting sufficient air for the combustion of elemental phosphorus, maintaining a temperature in the burner sufficiently high to prevent the condensation of 70 water, withdrawing phosphorus pentoxide and water vapor and absorbing the phosphorus pentoxide in the water as phosphoric acid in an absorption system.

4. A method of preparing phosphoric acid 80 comprising charging wet phosphorus having solid impurities incorporated therewith into a rotating combustion zone in which the wet phosphorus is distributed over the inner surface thereof, admitting a combustion supporting gas into the burner, burning the wet phosphorus therein to simultaneously form phosphorus pentoxide and water vapor free from solid impurities, maintaining the temperature in the burner sufficiently high to 85 prevent the condensation of water, then passing vapors to an auxiliary combustion zone, admitting an additional quantity of a preheated combustion supporting gas to the auxiliary combustion zone, withdrawing 90 phosphorus pentoxide and water vapor from the auxiliary combustion zone and absorbing the phosphorus pentoxide in the water as phosphoric acid in an absorption system.

In testimony whereof we have affixed 95 signatures.
